UNITED STATES PATENT OFFICE.

CHARLES V. LIMERICK, OF HAMILTON, OHIO.

LOCK TACK.

1,412,186.

Specification of Letters Patent. Patented Apr. 11, 1922.

Application filed December 15, 1920. Serial No. 431,000.

To all whom it may concern:

Be it known that I, CHARLES V. LIMERICK, a citizen of the United States, residing at Hamilton, in the county of Butler and State 5 of Ohio, have invented certain new and useful Improvements in Lock Tacks, of which the following is a specification.

This invention relates to improvements in tacks. The primary object of the invention 10 is the provision of a tack stamped from a single piece of sheet material.

A further object of the invention is the provision of a tack having a relatively long fastening prong, and auxiliary prongs of 15 shorter length, disposed about said central prong, and spaced therefrom.

A further object of the invention is the provision of a tack which is stamped from a single sheet of material, and including a 20 main fastening element, and auxiliary fastening elements, for locking and holding several objects, which might not overlie each other.

A further object of the invention, is the 25 provision of a locking tack of the above described character, which is simple in construction, economical in manufacture, and one which can be used to serve a variety of useful purposes.

Other advantages of the improved lock 30 tack will be apparent during the course of the following detailed description.

In the accompanying drawing, forming a part of this specification, and in which like 35 reference characters designate like parts throughout the same,

Figure 1 is a perspective view of the improved lock tack, showing the same provided with a plurality of arms.

Figure 2 is a bottom plan view of the type 40 of lock tack, shown in Figure 1 of the drawings.

Figure 3 is a cross sectional view of the improved lock tack.

Figure 4 is a cross sectional view through 45 a locking prong of the improved lock tack, and taken on the line 4—4 of Figure 3.

Figure 5 is a plan view of a modified form of lock tack.

Figure 6 is a side elevation of the modified 50 form shown in Figure 5.

Figure 7 is a cross sectional view showing a further modified type of lock tack.

Referring to the drawings in detail, where- 55 in for the purpose of illustration, is shown a preferred embodiment of my invention, the

numeral 10, designates a preferred form of lock tack, which is preferably formed of a single sheet of metal, and comprises the arms 11 and 12, in longitudinal alignment; 60 and the arms 13 and 14 in longitudinal alignment, the arms 11, 12, 13 and 14, all lying in the same plane and forming an integral structure. The arms 13 and 14, which are in longitudinal alignment, have the sections 65 15 and 16 struck respectively therefrom. The sections 15 and 16 are of equal length, and are so struck from their respective arms that the apertures 17, remaining in the arms 13 and 14 after the sections 15 and 16 have 70 been bent to their desired positions, terminate short of the ends 18 of the arms 13 and 14, in order to permit of sufficient rigidity of the arms.

The arms 11, 12, 13 and 14, radiate from 75 a common center 20, and it is at this common center 20, that the sections 15 and 16 remain integral with the structure 10. The sections 15 and 16 are first bent downwardly, and then struck inwardly, as at 21, and then 80 brought into abutting relation continuing throughout their lengths to provide a relatively long prong 22. The sections 15 and 16, may of course, be soldered, or welded together, to provide a more rigid or integral 85 structure.

It is preferred, that the sections 15 and 16 be pointed, as they are struck from the arms 13 and 14, and the points provided with the bevelled surfaces 23, to provide a better 90 structure. The lateral edges of the prong 22, are likewise provided with bevelled surfaces 24, to permit of more ready insertion of the prong 22 into an object. The ends 18 of the arms 13 and 14; and the ends 25 of 95 the arms 11 and 12, are provided with tapered downturned prongs 26, relatively shorter in length than the long prong 22.

The form of my invention shown in Figures 1 and 2, of course, may be provided 100 with any number of arms, to suit a particular need, it being the purpose of the arms, such as 11 and 12 to fasten different objects or different sections of the same object together. This lock tack could be used to advantage, in building construction, and especially in roofing a structure; where the meeting ends of several sections of roofing could be fastened to the roof, by the different arms of the tack 10.

In the modified form as shown in Figures 5 and 6, the tack 30 is provided with but two 110

arms 31 and 32, in longitudinal alignment. Each of the arms 31 and 32, have a section of material 33, struck therefrom, and bent inwardly and downwardly similar to the 5 sections as hereinbefore described for Figure 1. The ends 34 of the arms 31 and 32, are provided with the downturned arms 35, relatively shorter in length than the prong 36, as provided by the sections 33. This 10 type of lock tack, can be used to advantage, where it is merely desired to secure two sections of material or objects together.

In the form shown in Figure 7, a single section of material 40 is struck from an arm 15 41, of a tack structure 42, and first bent inwardly as at 43, and then bent downwardly to provide a prong, in itself. The end 44 of the prong 40 is pointed, to permit of its ready insertion into an object. The section 20 of metal taken from the arm 45 of this type of lock tack, is completely severed from the body of the tack, it being deemed superfluous. Otherwise the structure of this modified form of lock tack is the same as 25 above set forth for Figure 1 of the drawings, the ends of the arms 41 and 45, being provided with the downturned prongs 46, relatively shorter in length than the prong 40.

30 It can be seen from the foregoing description, that a lock tack has been perfected, formed of a single sheet of material; in which the prongs of said tack are of sufficient rigidity to effectively function as a 35 tack, in which the prongs are completely embedded in an object, and are not adapted to be turned aside or in any way mutilated.

It is to be understood that the form of my invention herewith shown and described, 40 is to be taken as a preferred example of the

same, and that various changes in the shape, size and arrangement of parts, may be resorted to, without departing from the spirit of the invention, or the scope of the subjoined claims.

45

I claim:

1. A tack comprising a body portion provided with sections struck therefrom, said sections being bent centrally of said body portions to lie in abutting relation to form 50 a relatively long fastening prong, and smaller prongs formed on the longitudinal ends of said body portion.

2. A tack, comprising a body portion, pointed sections struck therefrom upon each 55 side of the transverse center thereof, said pointed sections being bent inwardly and downwardly to lie in abutting relation, to provide a relatively long fastening prong, the lateral edges of said prong being 60 bevelled.

3. A tack, comprising a body portion, pointed sections struck therefrom upon each side of the transverse center thereof, said 65 pointed sections being bent inwardly and downwardly to lie in abutting relation, to provide a relatively long fastening prong, the lateral edges of said prong being bevelled, and small end pointed prongs upon the longitudinal ends of said body portion. 70

4. A tack, comprising a body portion, formed of a plurality of arms radiating from a common center, certain of said arms having pointed sections struck therefrom and fastened to said body portion at its common center, said sections bent downwardly to lie in abutting relation, to provide a fastening prong for securing the edges of articles that do not overlap. 75

CHARLES V. LIMERICK.
